UNITED STATES PATENT OFFICE.

CHARLES N. KOCH, OF KANE, PENNSYLVANIA.

TYPE-WRITER.

1,258,688.

Specification of Letters Patent. Patented Mar. 12, 1918.

Application filed March 13, 1917. Serial No. 154,431.

To all whom it may concern:

Be it known that I, CHARLES N. KOCH, a citizen of the United States, residing at Kane, in the county of McKean, State of Pennsylvania, have invented a new and useful Type-Writer, of which the following is a specification.

My present invention consists of a novel construction of mechanism which can be applied to any desired or conventional type of typewriter for effecting the automatic return of the paper carriage to its initial position when it has reached the end of the line or any predetermined point in its travel.

It further consists of novel carriage reversing mechanism which is connected to and actuates novel means for partially rotating the platen to advance the paper into proper position to have printed thereon the next line.

It further consists of a novel construction of a tension device and novel means for reversing it.

It further consists of a novel construction and arrangement of a buffer or guard member which serves to prevent the type from accidentally coming in contact with the paper on the platen, while the carriage is being reversed or returned to its initial or starting position.

It further consists of novel means for increasing the tension of the tension device during the normal operation of the typewriter.

Other novel features of construction and advantage will hereinafter more clearly appear in the detailed description of my invention.

For the purpose of illustrating my invention, I have shown in the accompanying drawings, a typical embodiment thereof, which is at present preferred by me, since this embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a sectional elevation of a typewriter embodying my invention,

the section being taken on the line 1-1 of Fig. 2.

Fig. 2 represents a top plan view of a portion of a typewriter, certain parts having been omitted for the sake of clearness of illustration.

Fig. 3 represents a sectional plan view on line 3-3 of Fig. 1.

Fig. 4 represents a section on line 4-4 of Fig. 1.

Fig. 5 represents a sectional view on line 5-5 of Fig. 4.

Fig. 6 represents a sectional view on line 6-6 of Fig. 4.

Fig. 7 represents a section on line 7-7 of Fig. 4.

Fig. 8 represents a rear elevation of a portion of the track carriage.

Fig. 9 represents a perspective view of a rock shaft and a connection therefrom.

Similar numerals of reference indicate corresponding parts in the figures.

Referring to the drawings:

1 designates the housing of the typewriter in which the keys 2 and their levers 3 are mounted in any desired or conventional manner, and operatively connected with the type bars 4 in order to actuate them. 5 designates the release key which controls the return of the platen carriage to its initial or starting position and this key is carried by a lever 6, which is fulcrumed on a rod 7 journaled in the housing. Each lever 3 has connected thereto or integral therewith an arm 8, to which is pivotally connected one end of a link 9, the other end of said link being pivotally connected to a pawl actuating lever 10, which is fulcrumed at 11.

12 designates a spring actuated pawl carried by the lever 10 and co-operating with a ratchet wheel 13. The lever 10 also carries a spring actuated pawl 14 co-operating with the ratchet wheel 13 and serving as a detent. The ratchet wheel 13 is mounted on a shaft 15 journaled in the housing, and this shaft 15 carries a worm 16 which meshes with a worm wheel 17, which is loosely mounted on a vertically disposed shaft 18 journaled in the housing of the machine.

The upper face of the worm wheel 17 is provided with the clutch teeth 19 which co-operate with the teeth of a clutch member 20, which is keyed to the shaft 18 by means

of the key 21 so that the clutch member 20 is longitudinally slideable on the shaft 18 and rotates in unison therewith.

22 designates a disk fixed to the shaft 18 and interposed between this disk and the clutch member 20 is a spring 23. The shaft 18 has secured to its upper end a friction disk 24 which is in frictional engagement with a disk 25 mounted on a shaft 26 journaled in the housing 1. The friction disks 24 and 25 are preferably surrounded by a split ring 27.

28 designates a clutch collar loosely mounted on the shaft 26 and connected by means of a clutch arm 29 with the tension release lever 6, as will be best understood by reference to Figs. 1 and 4. 30 designates a tension device which is provided with a side disk 31 rotatable on the clutch collar 28 and secured to a ring 32 by means of fastening devices 33. The outer periphery of the ring 32 is provided with the annular slots or grooves 34 and 35, respectively. In the groove 34 is located a tape 37, one end of which is fixed to the bottom wall of the groove, the other end thereof being secured to the right hand portion of the platen carriage 36.

37 designates a tape located in the groove 35 and having one of its ends fixed to the bottom wall of such groove, its other end being secured to the left hand portion of the platen carriage 36, as will be understood by reference to Fig. 2.

35 The side disk 31 has fixed thereto in any desired manner a locking disk 38, which is provided near its outer periphery with the radial grooves 39, with the walls of which one end of a rod 40 is adapted to engage. The other end of the rod 40 is adapted to interlock with the walls of the radial grooves 41 of a locking disk 42, which is loosely mounted on the shaft 26 and is provided with a gear 43, which intermeshes 45 with the idlers 44, which are rotatably mounted on a stationary plate 45 secured to the housing by fastening devices 46. The idlers 44 mesh with an internal gear 47 forming a part of the ring 32.

50 48 designates a spring, one end of which is fixed to the shaft 26 at 49 in any desired manner, and the outer end of said spring is connected to the locking rod 40 which is carried by an arm 50 fixed to the clutch sleeve 28, as will be best understood by reference to Fig. 4. The shaft 26 has secured thereto in any desired manner a ratchet disk 51, the teeth of which co-operate with the ratchet teeth 52 formed in the hub 60 of a handle 53, which latter is loosely mounted on the shaft 26, thereby providing for the manual winding up of the spring 48, if such action at any time becomes necessary.

The clutch releasing lever 6 is provided 65 with a pin 54 which passes through a slot

55 in an arm 56, which latter is secured to a rock shaft 57 journaled in the housing 1. The rock shaft 57 is provided with an arm 58, see Fig. 1, which is provided with a roller 59 adapted to bear against a rod or 70 bar 60 which is supported on a rock shaft 61.

62 designates a spring, one end of which is connected with the rod or bar 60, and its other end is fixed to a stationary point 75 of the housing. The rock shaft 61 has its ends journaled in the platen carriage 36 and has a polygonal contour which is slideable in a similar shaped aperture in the upper end of the bar 60. Secured to the rock shaft 61 at one end is an arm 63 which is provided with a slot 64 at its upper end and into this slot extends a pin 65 carried by a plunger 66, on which latter is pivotally mounted a spring actuated double pawl 67 which engages the teeth of the ratchet 68 in 85 order to advance the platen 69.

In order to prevent the type on a type bar 4 from being brought into engagement with the platen or the paper thereon during the reverse travel of the platen carriage due to 90 the accidental operation of one of the keys, I provide a guard or buffer 70 which is slideable in a stationary guide 71, and the lower end of such member 70 passes through a slot 72 in an arm 73 fixed to the lower 95 end of the bar 60. The lower end of the guard or buffer 70 is provided with a stop member 74 and the bar 70 terminates in an arm 75 between which and the arm 73 is interposed a spring 76. Fixed to the housing of the machine in the usual manner is a notched bar 77, see Figs. 1 and 8, on which is slideable a shoe 78 having a pin 79 which passes through a stop arm 80, with which is adapted to contact a stop 81 on the platen 100 carriage 36. The stop arm 80 is provided with a tension device 82. The stop arm 80 has its lower end deflected at an angle and adapted to engage the clutch arm 29 in order to move the latter downwardly. 110

The split ring or band 27, see Fig. 7, forms a friction band, one end of the sections of which are pivotally connected as at 83, and the opposite ends are adapted to have passed through them an adjusting 115 screw 84 which is provided with a nut 85, between which and one of said ends is interposed a spring 86.

The operation of my novel typewriter will now be apparent and is as follows:— 120

The ordinary key-board is operated in the usual manner and during such operation the automatic winding up of the spring 48 of the tension device 30 is effected due to the actuation of the arms 8 and the pawls 12 125 and 14, it being understood that each one of the key levers is provided with an arm 8 and its adjuncts. If the operator desires to return the carriage to its initial or starting position, the key 5 is pressed downwardly, 130

thereby causing the clutch rod 29 to move the locking rod 40 out of engagement with the walls of a groove 39 and into engagement with the walls of a groove 41, and 5 owing to the provision of the gear 43, the idlers 44 and the internal gear 47, the ring 32 of the tension device 30 will revolve in a reverse or unwinding direction and cause the platen carriage to be returned to its 10 initial or starting position.

When the key 5 is pressed downwardly to effect the return of the platen carriage to its initial position, the rock shaft 57 is actuated to cause the roller 59 to move the lower 15 end of the bar 60 laterally, thereby rocking the arm 63 and causing the pawl 67 to advance the platen one or more spaces according to its adjustment. During this movement of the bar 60, the buffer 70 is moved 20 up into position in front of the platen so that in case the operator should accidentally actuate one of the regular keys of the keyboard, the type on its type bar would strike the buffer and would not come into engagement with the paper on the platen. By adjusting the position of the shoe 79, the clutch rod 29 can be actuated to bring the platen carriage to a stop at any desired point during 25 its return to its starting position.

30 If at any time it is desired to increase the tension of the spring, this can be accomplished manually by actuating the handle 53 in the proper direction, as is apparent.

It will now be apparent that I have devised 35 a novel and useful typewriter, which embodies the features of advantage enumerated as desirable in the statement of the invention and the above description, and while I have, in the present instance, shown 40 and described a typical embodiment thereof which will give in practice satisfactory and reliable results, it is to be understood that this embodiment is susceptible of modification 45 in various particulars without departing from the spirit or scope of the invention or sacrificing any of its advantages.

Having thus described my invention, what I claim as new and desire to secure by Letters Patent, is:—

50 1. In a typewriter, a platen carriage, a tension device therefor to move it in either direction, and comprising a ring having a plurality of tapes connected therewith and with said carriage, a disk having radial 55 grooves and secured to said ring, a disk having radial grooves and intergeared with said ring to effect its rotation in a reverse direction, a winding shaft, a spring having one end fixed to said shaft, a locking member 60 carried by the other end of said spring and adapted to interlock with the walls of a groove of one or the other of said rings, and a key-controlled clutch connected with said locking member.

65 2. In a typewriter, a platen carriage, a ten-

sion device therefor to move it in either direction, and comprising a ring having a plurality of tapes connected therewith and with said carriage, a disk having radial grooves and secured to said ring, a disk having radial grooves and intergeared with said ring to effect its rotation in a reverse direction, a winding shaft, a spring having one end fixed to said shaft, a locking member carried by the other end of said spring and adapted to interlock with the walls of a groove of one or the other of said rings, a key-controlled clutch connected with said locking member, and means actuated by said carriage to return said clutch to its initial position and cause said locking member to interlock with a groove of the ring secured to the disk.

3. In a typewriter, a platen carriage and a tension device therefor, comprising a winding shaft, a spring connected therewith, a 85 grooved ring, tapes having one end secured in their respective grooves of said ring and secured to said carriage, a member intergeared with said shaft to cause it to rotate in a reverse direction, a locking member carried at the free end of said spring and adapted to interlock with said ring or with said first member, and means to actuate said locking member.

4. In a typewriter, a platen carriage and a tension device therefor to move it in either direction, and comprising the following instrumentalities:—a ring having a plurality of tapes connected therewith and with opposite ends of said carriage, a disk secured to said ring, a second disk, a winding shaft, 100 a gear thereon, idlers intergeared with said gear and with said ring, a spring fixed to said shaft, a locking member secured to the free end of said spring and adapted to interlock with either disk, and a key-controlled lever operatively connected with said locking member to actuate it.

5. In a typewriter, a carriage and a tension device therefor comprising the following instrumentalities:—a winding shaft, a gear thereon, a disk having idlers meshing with said gear and intergeared with said ring, a disk fixed to said ring, tapes secured to said ring and connected with opposite 115 ends of said carriage, a spring having one end fixed to said shaft, a locking member secured to the other end of said spring and adapted to interlock with one or the other of said disks, a key-controlled lever operatively 125 connected with said locking member to actuate it, and means controlled by said key-controlled means to advance the platen during the reverse movement of said platen carriage.

6. In a typewriter, a platen carriage, a winding shaft, a spring having one end connected with said shaft, a ring connected with said carriage to move it in a forward or a reverse direction, reversing 130

- mechanism connecting said ring and said shaft and loosely mounted on said winding shaft, and means to connect the free end of said spring with said ring or with said reversing mechanism. 60
7. In a typewriter, a platen carriage, a sectional winding shaft, frictional means engaging said sections, a spring having one end secured to said shaft, a rotatable ring connected to said platen carriage to move it in either direction, reversing mechanism intergeared with said shaft and with said ring and loosely mounted on said winding shaft, and means to connect the free end of 10 said spring with said ring or with said reversing mechanism. 65
8. In a typewriter, a sectional winding shaft, friction means engaging said shaft, a clutch member keyed to said shaft, a tension device therefor, a worm coöperating with said clutch member, pawl and ratchet mechanism operatively connected with said worm and adapted to be controlled by the regular key-board, a spring having one end 20 connected with said winding shaft, a rotatable member on said winding shaft, a platen carriage connected with said member to be moved in either direction, reversing mechanism, and means to connect said spring with either said rotatable member or said reversing mechanism. 70
9. In a typewriter, a sectional winding shaft frictionally connected, a tension device coöperating therewith, a platen carriage controlled by said tension device, key-controlled means to revolve said winding shaft to increase the tension of said tension device, reversing mechanism adapted to 25 form a connection between said tension device and said winding shaft and loosely mounted on the latter, and key-controlled means to cause said tension device to coöperate directly with said shaft, or with said shaft through said reversing mechanism. 75
10. In a typewriter, a winding shaft, a tension device coöperating therewith, a platen carriage controlled by said tension device, a friction drive for said shaft to increase the tension of said tension device and 30 key-controlled, reversing mechanism adapted to form a connection between said tension device and said winding shaft and loosely mounted on the latter, key-controlled means to cause said tension device to coöperate directly with said shaft, or with said shaft through said reversing mechanism, a platen, and means actuated by said key-con- 80
- trolled means to advance said platen during the return movement of said platen carriage. 85
11. In a typewriter, a winding shaft, a tension device coöperating therewith, a platen carriage controlled by said tension device, a friction drive for said shaft to increase the tension of said tension device and key-controlled, reversing mechanism adapted to form a connection between said tension device and said winding shaft and loosely mounted on the latter, key-controlled means to cause said tension device to coöperate directly with said shaft, or with said shaft through said reversing mechanism, a platen, the type, and means actuated by said key-controlled means to prevent the type being moved into operative relationship with the 90 platen during the return movement of the platen carriage. 95
12. In a typewriter, a winding shaft, a platen carriage, a spring having one end connected with said shaft, a ring connected with 100 said platen carriage to impart a forward or a reverse movement to it, reversing mechanism loosely mounted on said winding shaft and intergeared with said ring, a stop on said carriage, an arm longitudinally adjustable with respect to said stop and positioned in the path of said stop, means actuated by said arm to move the free end of said spring to control the travel of said platen carriage in its reverse movement, and key-controlled means to release said spring to effect a reverse movement of said carriage. 105
13. In a typewriter, a platen carriage, a winding shaft having tension means, a spring having one end connected with said shaft, a ring connected with said platen carriage to impart a direct or a reverse movement to it, reversing mechanism loosely mounted on said winding shaft and intergeared with said ring, a shoe adjustable with respect to said carriage, a spring pressed arm carried by said shoe, a stop on said carriage to engage said arm, means actuated by said arm to operate the free end of said spring to control a predetermined length of travel of said platen carriage in its reverse movement thereof, and key-controlled means to release said tension means to effect the reverse movement of said carriage. 110
